MERCHANDISE

N° 3167

Design, or new pattern on enlarged
scale of a $\frac{3}{4}$ top plate for watches.

United States Patent Office.

EUGENE PAULUS, OF PHILADELPHIA, PENNSYLVANIA.

Design No. 3,167, dated August 25, 1868.

DESIGN FOR TOP PLATE FOR WATCH.

The Schedule referred to in these Letters Patent and making part of the same.

TO ALL WHOM IT MAY CONCERN:

Be it known that I, EUGENE PAULUS, of the city of Philadelphia, in the county of Philadelphia, and State of Pennsylvania, have originated and designed a new and improved Pattern for the Top Plate of a Watch, of which the following is a full, clear, and exact description, reference being had to the accompanying specimens, or drawings, making part of this specification, in which—

Figure 1 represents a top view of the plate, as seen when the case and cap of the watch are open, the main feature being delineated by the red boundary line at X.

Figure 2 represents an inside view of the reversed plate, being removed from the pillars of the dial or front plate. R S is the recess made in its thickness, to hold the click-spring.

The object of this new design is a new arrangement to have the balance-wheel on the left and the winding-arbor on the right side, being seen when opening the case, which is a noticeable and useful improvement of that which is usually done. The winding-arbor being opposite the opening-joint of the case-cover and cap, they cannot interfere with or impede the fingers when winding the watch, which is done more easily, and with less danger of breaking the main-spring, and, by this new system, both joints of the case-cover can be placed opposite the stem of the watch.

The configuration of this three-quarter plate may be generated by the ordinary circular line around the centre, and a peculiar carving into the diameter, so as to leave in view a larger part of the work than usual, being formed by a circular curve around the winding-arbor, deepening into the diameter by two peculiarly symmetric curves, joining the centre on one side, and the generating-circle on the other. Besides, a double symmetric curve is formed around the balance-rim on each side of the circular curve around the pallet-jewel, and joining the centre on one side, and the generating-circle on the other, so as, the movement being in the case, to joint the inside circle by the two angles or sharps corners A B.

H I J denotes a raised or upper part, managed on the surface of the plate, delineating a curve symmetric to K L, and forming a thicker part, in which are made proper recesses O P for the click and ratchet-wheel.

The top plate is held on the pillars of the front plate by the three screws a b c, placed at equal distance of each other, and d is a peculiar screw to fasten the movement in the case. F is the balance-bridge. G is the double-cap-jewelled bridge, being represented here in order to show the general appearance and feature of this new style of watch-frame.

What I claim, and desire to secure by Letters Patent, is—

The design or new pattern for a three-quarter top plate of a watch-movement, with a rising or upper part on its surface for the click-work, the whole formed and delineated by the red boundary lines, and quoted by the letter X, substantially as described and represented in the accompanying drawings.

Philadelphia, July 31, 1868.

E. PAULUS.
